Primary Examiner — Martie K Holtje*(74) Attorney, Agent, or Firm* — Hunton & Williams LLP(57) **CLAIM**

I claim the ornamental design for a parking meter housing, as shown and described.

DESCRIPTION

FIG. 1 is a top, right front perspective view of a parking meter housing showing my new design;

FIG. 2 is a front view thereof drawn to a reduced scale;

FIG. 3 is a rear view of FIG. 2;

FIG. 4 is a right side view of FIG. 2;

FIG. 5 is a left side view of FIG. 2;

FIG. 6 is a top plan view of FIG. 2;

FIG. 7 is a bottom plan view of FIG. 2;

FIG. 8 is a second top, right front perspective view of FIG. 2; FIG. 9 is a top, rear perspective view drawn to the scale of FIG. 1; and,

FIG. 10 is a bottom front perspective view drawn to the scale of FIG. 1.

The additional structure depicted by broken lines in FIG. 8 has been shown for the purpose of illustrating environment that forms no part of the claimed design. The broken lines in FIG. 7 represent boundaries the areas within which form no part of the claimed design.
